UNITED STATES PATENT OFFICE

108,853

DESIGN FOR A COMBINED PLEATED AND EMBROIDERED FABRIC

Louis Kaufman, New York, N. Y.

Application November 5, 1937, Serial No. 72,628

Term of patent 14 years

To all whom it may concern:

Be it known that I, Louis Kaufman, a citizen of the United States of America, residing in New York city, in the Borough of Manhattan, county and State of New York, have invented a new, original, and ornamental Design for a Combined Pleated and Embroidered Fabric, of which the following is a specification, reference being had to the accompanying drawing, forming part thereof, wherein,

The figure is a fragmentary edge view of a piece of combined pleated and embroidered fabric showing my new design.

The fabric comprises narrow pleats separated and uniformly spaced in combination with rows of embroidery positioned medially on the pleats and consisting of single, relatively short stitches widely spaced.

I claim:

The ornamental design for a combined pleated and embroidered fabric, substantially as shown and described.

LOUIS KAUFMAN.
